HANDBAG FRAME

Samuel Koret, Flushing, N.Y.

Application November 3, 1958, Serial No. 53,250

Term of patent 3½ years

(Cl. D87—2)

Fig. 1 is a perspective view of a handbag frame showing my new design;

Fig. 2 is a similar view with the frame partially closed; and

Fig. 3 is an end view of the same, showing the handbag frame in fully closed position.

I claim:

The ornamental design for a handbag frame, substantially as shown.
